UNITED STATES PATENT OFFICE.

LUIGI VECCHIO, OF SCHENECTADY, NEW YORK, ASSIGNOR TO ELECTRICAL INVENTIONS & DEVELOPMENT COMPANY, OF SCHENECTADY, NEW YORK, A CORPORATION OF NEW YORK.

FUSE PLUG.

Application filed January 4, 1922. Serial No. 526,935.

This invention is a thermal cut out device for electric circuits.

One of the objects of the invention is to provide a fuse plug of simple construction, so constructed that the fusible element may be readily renewed, thereby permitting of the indefinitely continued use of the remaining elements of the device. A further object is to provide simple means by which the ends of the fusible element may be anchored in position, to insure establishment of the circuit through the plug. A further object is to provide a fusible element which may be applied to the plug by unskilled persons, without likelihood of mistake as to the amperage the plug is to carry.

The invention will be hereinafter fully set forth and particularly pointed out in the claims.

20 In the accompanying drawing:—

Figure 1 is a longitudinal sectional view illustrating a fuse plug constructed in accordance with the invention. Figure 2 is a top plan view. Figure 3 is a bottom plan view. Figure 4 is a longitudinal sectional view illustrating a slight modification.

Referring to Figures 1, 2 and 3 of the drawing, 10 designates an insulating block, constructed of porcelain, or other suitable insulating material, open at one end 11, and closed at the other, as indicated at 12. The closed end is provided with a boss 13. Enclosing the insulating block is a screw shell 14, forming the shell contact in a manner well understood in the art, said shell having an opening to receive the boss 13. Said boss and said opening are of any desired shape which will prevent relative rotation of these two elements.

40 The wall of the block 10, near the open end, is provided with a bore shaped to receive a metal contact tube 15, rigidly secured to the interior of the shell 14, in any desired manner which will insure electrical contact therewith. The exterior of the said block 10 is provided with a groove 16, in alignment with said bore, to provide the necessary clearance for movement of said tube, while the parts are being assembled.

50 The closed end 12 of the insulating block 10 is provided with a bore, in which is secured a metal sleeve 17. The fuse wire 18,

is secured at one end to a split plug 19, having resilient arms normally separated at their free ends, said arms being shaped to engage the bore of said sleeve 17, for the purpose of anchoring the contiguous end of the fuse wire in place. Said clip is provided with a head 20, which serves as the center contact of the device. The other end of the fuse wire is inserted into the open end of the tube 15, as shown in Figure 1, and is anchored in place by means of a suitable device, such as the split plug 21.

The open end of the plug is normally closed by a cap 22, having a threaded portion 23, engaging a complementary portion of the insulating block 10. Said block is provided with one or more lugs 24, which are positioned to be engaged by complementary lugs 25, projecting from the inner face of the cap. Both sets of lugs are positioned inwardly from the periphery a substantial distance so as to be concealed when the cap is in place. By means of these lugs the plug may be screwed in its socket by turning the cap in the proper direction.

In practice, the elements of the plug are assembled by placing the block 10 within the shell 14, relative rotation of these parts being prevented by means of the boss 13, and the tube 15. The fuse wire is then passed inwardly from the outside, through the sleeve 17, until the arms of the split plug 19 are brought into frictional engagement with said sleeve, thereby removably anchoring the contiguous end of the wire 18 in place. The other end of the said wire is passed over the edge of the open end of the block 10, and bent down into the contiguous end of the tube 15, where it is anchored by the split plug 21. The cap 22 is then applied, and the plug is ready for use.

In operation, the device is applied to its socket in a manner well understood in the art. The head 20 of the split plug 19 serves as the center contact, and the wire 18 is connected with the shell contact, through the medium of the tube 15. When the fuse has "blown", the cover 22 is removed, the plug 19 and the wire attached thereto are withdrawn, and plug 21 is also withdrawn. A new fuse wire may then be substituted for the one which has been destroyed, by in-

serting and connecting the new wire in the manner already described. To avoid mistake, the amperage for which the wire is made, may be stamped on the head 20 of the 5 plug 19.

In Figure 4 is illustrated a slight modification. In this form the insulating block 25 is provided with a reduced portion to which the shell 26 is permanently secured. 10 Said block is also provided with a bore to receive the sleeve 27, which may be connected to the shell 26, in any desired manner, such as punching in the shell, as indicated at 28, and forming an electrical union 15 of the parts by solder. The fuse wire is anchored in position in the manner already described.

The advantages of the invention will be readily apparent to those skilled in the art

20 to which it appertains. It will be particularly observed that when the fuse blows, none of the elements of the device is destroyed, except the fuse wire. By constructing the parts so that the destroyed wire may be replaced, the remaining parts may be used indefinitely. It will also be noted, that the parts are so arranged that the services of an expert are not required, for the purpose 25 of making repairs, but that circuit through the plug is assured, just as soon as the ends 30 of the wire are connected to their respective anchoring points. An important advantage is that binding screws and threaded parts for securing the fuse wire in place are dispensed with, thereby resulting in a reduction 35 in the cost of manufacture, and enabling replacements to be more rapidly accomplished without necessitating the use of tools such, for instance, as a screw driver.

40 Having thus explained the nature of the invention and described an operative manner of constructing and using the same, although without attempting to set forth all of the forms in which it may be made, or all 45 of the forms of its use, what is claimed is:—

1. A fuse plug comprising an insulating block, a screw shell enclosing said block and provided with an internal contact member having a bore therein, a fuse wire having 50 one end inserted into and retained within the bore of said contact member, and means anchoring the other end of said fuse wire in a manner to provide a center contact.

2. A fuse plug comprising an insulating block, a screw shell enclosing said block and provided with an internal tubular contact member, a fuse wire having one end inserted into and retained within one end of 60 said tubular contact member, and means anchoring the other end of said fuse wire in a manner to provide a center contact.

3. A fuse plug comprising an insulating block, a screw shell enclosing said insulating block and provided with a contact member 65 having a bore therein, a fuse wire having

one end inserted into the bore of said contact member, a split plug shaped to be inserted into the bore of said contact member to anchor the contiguous end of said fuse wire, and means anchoring the other end of 70 the fuse wire in a manner to provide a center contact.

4. A fuse plug comprising an insulating block having a longitudinal bore therein leading to the top of the block, a contact shell enclosing said block and having an elongated contact member projecting through said bore, said contact member being exposed at one end, a fuse wire having one end engaging an end of said contact 80 member, and means connected with the other end of said fuse wire and removably engaging the insulating blocks to form a center contact.

5. A fuse plug comprising an insulating block, a contact shell enclosing said block, a tubular contact member secured at one end to said shell and projecting through said bore, a fuse wire having one end inserted into and retained within the tubular contact, and means anchoring the other end of 90 said fuse wire in a manner to provide a center contact.

6. A fuse plug comprising an insulating block having a longitudinal opening there- 95 in, a contact shell enclosing said block, a tubular contact secured at one end to said shell and projecting through said opening, a fuse wire having one end inserted into the free end of said tubular contact, a split 100 block retaining the inserted end of said wire in position, and means anchoring the free end of said fuse wire in a manner to provide a center contact.

7. A fuse plug comprising an insulating 105 block closed at one end and open at the other, said closed end having a bore there- in, a contact shell enclosing said block, a fuse wire having a split plug permanently united thereto and shaped to frictionally engage 110 said bore and form a center contact, whereby the wire and the plug may be inserted and removed as a unit, and a tubular contact member extended longitudinally through the wall of the insulating block and 115 having one end rigidly secured to said shell, the other end of said tubular contact member being exposed and engaged by the down- turned end of said fuse wire.

8. A fuse plug comprising an insulating 120 block closed at one end and open at the other, said closed end having a bore there- in, a contact shell enclosing said block and provided with a contact member having one end exposed contiguous to the open end 125 of said block, and a fuse wire having one end in frictional engagement with said bore and forming a center contact, the other end of said wire extending around the open end 130 of the insulating block and projecting into

and having frictional engagement with the exposed end of said contact member.

9. A fuse plug comprising an insulating block closed at one end and open at the other, said closed end having a bore therein, a second bore being formed longitudinally in the wall of said block, a contact shell enclosing said block, a tubular contact located in the last named bore and secured to said contact shell, a fuse wire having one end passed through and in frictional engagement with the bore in the closed end of the insulating block and provided with means forming a center contact, the other end of said wire being inserted into an end of said tubular contact, and a removable

anchoring member for the last mentioned end of said wire.

10. A fuse plug comprising an insulating block, a contact shell enclosing said block, a center contact, a fuse wire in circuit with said center contact and said shell, and a screw cap engaging said insulating block, said cap and said block having complementary lugs arranged to abut when the cap has been rotated to a predetermined position, said lugs being positioned inwardly a substantial distance from the periphery of the block.

In testimony whereof I have hereunto set my hand.

LUIGI VECCHIO.
